L. G. MARSHALL.
RAILWAY CHAIR AND CROSS TIE.

No. 40,541.

Patented Nov. 3, 1863.

UNITED STATES PATENT OFFICE.

LOOMIS G. MARSHALL, OF PHILADELPHIA, PENNSYLVANIA, ASSIGNOR TO HIMSELF AND ANDREW COCHRAN, OF SAME PLACE.

IMPROVEMENT IN IRON RAILWAY CHAIRS AND CROSS-TIES.

Specification forming part of Letters Patent No. 40,541, dated November 3, 1863.

To all whom it may concern:

Be it known that I, LOOMIS G. MARSHALL, of the city of Philadelphia and State of Pennsylvania, have invented new and useful Improvements in Iron and Steel Railway Chairs and Cross-Ties; and I do hereby declare that the following is a full and exact description thereof, reference being had to the accompanying drawings, and to the letters of reference marked thereon, making a part of this specification.

The nature of my invention is an improved railway-chair, made of steel or iron, and its arrangement and combination with a tie and key.

To enable others skilled in the art to make and use my invention, I will proceed to describe its construction, as follows:

Figure 1 represents a view of the railway; Fig. 2, an end view, and Fig. 3 a view, of the chair.

A represents the ordinary T-rail, reversed, top down, the wide part (the base or flanged sides B) resting in the chair C, underneath, and fitting into the top groove of the chair, which is square-shaped, and has two similar grooves—one at top, lengthwise, and the other at bottom, crosswise. The rail slides into the top groove, and the cross-tie slides into and fits in the lower groove. The cross-tie D, being shaped like the lower part of the rail A, having a flange at each side that the sides of

the groove of the chair C clasp and bind firmly.

On the outside of rail A and on one side of tie D, between the rail and chair and between the tie and chair, a wedge-shaped key, E, is driven, which key is stayed by a pin driven through its narrow end. The chair thus holds the rail and tie firmly and securely.

Between the rail and the chair and between the chair and the tie I have an elastic or gutta-percha cloth, G. These pieces of rubber lining G give ease to the cars and prevent the tie and rail from breaking, rendering them free from sudden jars, and relieving them from the strain produced by the engine and making the road more durable. The whole is intended for easy and quick transportation and facilitating the building of railways at the cheapest cost possible.

What I claim as my invention, and desire to secure by Letters Patent, is—

1. The square-shaped double-grooved chair with its elastic rubbers, as herein described.
2. The arrangement and combination of the rail-chair and tie, arranged, constructed, and keyed together as herein described, and for the purposes set forth.

LOOMIS G. MARSHALL.
